Des. 180,346
Patented May 21, 1957

180,346

ANIMAL FEEDING DEVICE

Charles Weil, Los Angeles, Calif.

Application April 2, 1956, Serial No. 40,868

Term of patent 14 years

(Cl. D12—2)

FIG. 1.

FIG. 2.

FIG. 3.

FIG. 4.

FIG. 5.

Fig. 1 is a plan view of an animal feeding device showing my new design;

Fig. 2 is an inverted plan view thereof;

Fig. 3 is a side elevational view thereof;

Fig. 4 is a front elevational view thereof; and

Fig. 5 is a rear elevational view thereof.

I claim:

The ornamental design for an animal feeding device, substantially as shown.
